SMOKING PIPE

Alfred H. Behrman and Levi H. Eckhardt, Baraboo, Wis.; said Behrman assignor to said Eckhardt

Application March 11, 1935, Serial No. 10,411

1 Claim. (Cl. 131—12)

This invention appertains to tobacco users' appliances, and more particularly to a novel smoking pipe.

One of the salient objects of our invention is to provide a smoking pipe in which the smoke is cooled prior to entrance of the same in the user's mouth, and in which moisture, residue, etc., is confined in the stem and against admittance in the mouth with the smoke.

Another important object of our invention is to provide a smoking pipe of the above character, which can be readily and quickly taken apart to permit the thorough and expeditious cleaning thereof, whereby the pipe can be conveniently kept in a sanitary condition and the smoke passages kept clean for full passage of the smoke.

A further object of our invention is to provide a smoking pipe, in which the entire stem and bit is divided longitudinally, whereby the sections of the stem can be separated to expose the smoke passageways to view, so that the same can be readily cleaned, the sections of the stem being preferably united by a tongue and groove to permit the sections to be conveniently and quickly united, and whereby a substantially leak-proof joint will be had.

A further object of our invention is the provision of a mating tapered tongue and groove formed on the meeting faces of the stem sections, so that the sections can be effectively wedged together to form the desired tight joint, the lower section having a strike portion formed thereon, normally projecting beyond the bowl, so that said portion can be struck to facilitate the initial movement of the lower section when it is desired to take the sections apart.

A further object of our invention is to provide a smoke pipe in which the entire stem and bit are divided longitudinally and united by a tapered tongue and groove, one section being provided with a tortuous or circuitous passageway opening out through one end of the stem, and communicating at its opposite end with a passageway formed in the bowl and opening out through the other section of the stem.

A still further object of our invention is to provide a smoke pipe of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed,

and illustrated in the accompanying drawing in which drawing:—

Figure 1 is a longitudinal section through a smoking pipe, constructed in accordance with my invention;

Figure 2 is a bottom plan view of our improved pipe with the lower section of the stem removed;

Figure 3 is an enlarged detail end view of the upper stem section;

Figure 4 is a top plan view of the lower stem section removed from the pipe;

Figure 5 is an enlarged detail end view of the bottom stem section;

Figure 6 is a detail transverse section through the pipe taken on the line 6—6 of Figure 1, looking in the direction of the arrows.

Referring to the drawing in detail, wherein similar reference characters designate corresponding parts throughout the several views, the letter A generally indicates our improved pipe, which comprises the bowl 10 and the stem 11. The bit 12, as shown, is integrally connected with the stem. If preferred, the bowl and stem can be made integral and formed out of briar or similar hard wood, or the bowl can be made separate from the stem and detachably connected therewith. In such case, the stem can be formed from hard rubber or Bakelite, and the bowl can be formed from wood.

In the drawing, the bowl 10 has been shown formed separate from the stem, and its connection with the stem will be later described.

In accordance with our invention we divide the stem 11 longitudinally to provide an upper section 13 and a lower section 14. The sections 13 and 14 are detachably connected together by a mating tongue and groove. For the purpose of illustration, a dovetailed groove 15 is formed in the lower face of the upper section 13, and a dovetailed tongue 16 is formed on the lower section 14. The groove 15 and the tongue 16 are tapered toward the bowl end of the pipe so that when the sections are slid together, a wedging effect will be had to provide a tight joint. The lower pipe section 14 is provided with an outwardly projecting strike portion 17 which normally projects beyond the bowl 10 and the upper stem section 13 when the stem sections are united, and this portion 17 forms means for facilitating the striking of the lower stem section on an object to permit the initial loosening thereof, so that said lower stem section can be readily slid off of the upper stem section.

The forward end of the upper stem section 13 is provided with a cavity or socket 18, and the

removable bowl 10 has its lower face rabbeted to provide a flange 19 for reception in said socket. This forms a friction joint for uniting the bowl with the stem. A forwardly and laterally extending smoke passageway 20 is formed in the upper stem section and communicates with the cavity or socket 18 at one end and opens out through the lower face of the groove at its opposite end.

10 To form means for cooling the smoke as the same is drawn through the stem and to prevent the drawing of moisture, tobacco residue, etc., in the mouth with the smoke, the lower section 14 of the stem has its inner face provided with 15 a tortuous or circuitous passageway. This circuitous passageway defines side longitudinal passageways 21 and 22, and an intermediate longitudinal extending passageway 23. The forward end of the longitudinal passageway 21 communicates with a cavity 24 which is adapted to register with the smoke passageway 20 formed in the upper stem section 13 when the stem sections are united.

The other side longitudinal passageway 22 communicates at its out end with a smoke passageway or outlet 25 formed in the bit end 12 of the stem. The opposite ends of the intermediate longitudinal passageway 23 communicate with the opposite ends of the side longitudinal passageways 21 and 22. When the stem sections are united the inner wall of groove 15 closes the tops of the passageways and prevents leakage of smoke therefrom, but obviously a cork gasket, or the like, can be placed around the 35 circuitous passageway to prevent leakage.

In use of our improved pipe, the bowl is filled with tobacco in the ordinary way, and when the user draws on the pipe the smoke will be drawn down through the passageway 20 into the cavity 24 through the passageways 21, 23, 22, and out the passageway 25. Obviously, during the travel of the smoke through the passageways the same will be effectively cooled, and

the ends of the passageways will tend to prevent moisture and the like from entering the mouth of the user.

When it is necessary to clean the pipe, the strike portion 17 is tapped on an object, which loosens the sections, and the sections are then slid apart. Obviously, this exposes all of the passageways to view, and thus these passageways can be expeditiously cleaned and kept in a sanitary condition.

10 The pipe sections are united by simply sliding the tongue into the groove. If preferred, the forward end of the section 14 can carry a stop lug 26 for fitting in a groove 27 in the top stem section 13. This will prevent the bottom section 15 from being slid too far into the top section.

From the foregoing description, it can be seen that we have provided an exceptionally simple and durable pipe which will effectively cool the smoke, and which can be kept in a 20 sanitary or clean condition.

Changes in details may be made without departing from the spirit or the scope of our invention, but what we claim as new is:

A smoke pipe comprising a bowl and a stem having a bit, the stem including a pair of longitudinally extending companion sections, the sections being provided with a mating tongue and groove, the tongue and groove tapering toward the bowl end of the pipe, one of said sections having a smoke passageway therein communicating with the bowl, the other of said stem sections having a circuitous passageway opening out through the bit end of the stem and communicating with the first mentioned smoke passageway when the sections are united, and a strike portion formed on the forward end of the lower stem section normally projecting beyond the bowl whereby to facilitate the initial displacement of the sections when the same are to be separated.

ALFRED H. BEHRMAN.
